RESERVOIR SAFETY RAZOR

Hyman Resnick, 2983 N. 6th St., Harrisburg, Pa., and
Louis Shnidman, 1878 N. Clinton Ave., Rochester,
N.Y.Filed Dec. 28, 1962, Ser. No. 247,937
2 Claims. (Cl. 30—41)

This invention relates to a replaceable reservoir safety shaver.

An object of the present invention is to provide a replaceable reservoir safety shaver which lends itself to ready use, and requires no attention other than cleaning after a shaving operation with occasional replacement of a cartridge containing shaving lubricant.

Another object of the present invention is to provide a replaceable reservoir safety shaver which is easy to operate, and which is positive in action.

A further object of the present invention is to provide a replaceable reservoir safety shaver which is constituted of few parts, is appealing to prospective users, and is commercially practical.

Other objects and advantages of the present invention will become apparent from the following description taken in conjunction with the accompanying drawings, in which:

FIGURE 1 is a perspective view of the replaceable reservoir safety shaver according to the present invention;

FIGURE 2 is a transverse sectional view taken on the line 2—2 of FIGURE 1;

FIGURE 3 is a longitudinal sectional view taken on the line 3—3 of FIGURE 2;

FIGURE 4 is a plan sectional view taken on the line 4—4 of FIGURE 2;

FIGURE 5 is an exploded view of the replaceable reservoir safety shaver of FIGURE 1;

FIGURE 6 is a perspective view of the shaving head removed from the replaceable reservoir safety shaver of FIGURE 1, and laid down so that the bottom is faced out;

FIGURE 7 is a view similar to FIGURE 3, with parts broken away, showing the valve member after execution of sliding movement in one direction with one of its passages in communication with the plunger shifted to open position and in communication with one of the passageways of the head; and

FIGURE 8 is a plan view of the shaving head of FIGURE 1, with the razor blade mount removed, showing the valve member in inoperative position and the relation of its vertical passages to the passageways in the shaving head.

Referring to the drawings, numeral 10 designates a replaceable reservoir safety shaver of the present invention. This shaver comprises a shaving head 12, a replaceable cartridge 14 serving as a reservoir and containing shaving lubricant under pressure connected to the head 12, an open top shell 16 encompassing the replaceable cartridge and having the open top releasably engaging the shaving head 12 and serving as a handle, and a safety razor blade mount 18 overlying and fixedly attached to the top of the shaving head, the mount being adapted to support a blade so that a cutting edge overlies the discharge end of a passageway provided in the adjacent side of the shaving head 12.

The shaving head 12 has a top 20, a bottom 21, and a plurality of opposed sides between the top 20 and bottom 21. There are two pairs of opposed sides, the one

2

pair comprising the opposed sides 22 and 23, and the other pair comprising the opposed sides 24 and 25. The head is provided with a transverse bore 26 intermediate the top 20 and the bottom 21, the bore extending between one of the pair of opposed sides 22 and 23 and opening out of the sides 22 and 23. The head 12 has a passageway 27 which extends along each of the other pair of opposed sides 24 and 25 with one end opening into the bore 26 and the other end opening out of the top 20 of the head 12. Specifically, each passageway 27 is of a configuration, FIGURES 7 and 8, simulating a V with the apex end 28 constituting the one end opening into the bore 26 and the free ends of the legs 29 opening out of the top of the head 12.

The bottom 21 of the head 12 is provided with a recess 17, FIGURES 6 and 7, which extends inwardly and terminates at a point adjacent the bore 26, and an outlet port 19 extends from the terminating point of the recess 17 and opens into the bore 26.

A valve member 30 is mounted in the bore 26 of the shaving head 12 for sliding movement in opposite directions, the valve member, FIGURES 3, 5, 7 and 8, being provided with spaced vertical passages 31 and horizontal grooves 31' on its top face. The valve member 30 is formed with an embracing means or groove 32 extending transversely across its under face, the groove being disposed midway between the passages 31. The purpose of this means or groove 32 will become subsequently apparent.

Operatively connected to each end of the valve member 30 and normally projecting out of the adjacent sides 22 or 23 is a spring-biased operating button 34, the button serving to effect the sliding movements of the valve member 30 in the respective directions responsive to application of a compressive force applied to a selected button. Specifically, the valve member 30 at each end terminates in a stem 30' on which is press fitted a button 34, and circumscribed about the stem is a coil spring 33, one end of the coil spring 33 bearing against the button

34 and the other end of the coil spring 33 bearing against a shoulder 35 provided in the head 12, as clearly shown in FIGURE 4. Application of a compressive force to the button 34 adjacent the side 22, FIGURE 3, brings the passage 31 and horizontal groove 31' on its top face

45 adjacent the side 22, FIGURE 7, into communication with the said one end or apex end 28 of the passageway 27 in the side 24 of the shaving head 12. Application of a compressive force to the button adjacent the side 23, FIGURE 3, brings the other of its passages 31 and horizontal groove 31' on its top face, FIGURE 8, into communication with the said one end or apex end 28 of the passageway 27 in the side 25.

The replaceable cartridge 14 has a valve plunger 40 which controls the flow of shaving lubricant therefrom, the valve plunger being normally spring-biased to a closed position, as shown in FIGURE 3. Specifically, the valve plunger 40 is mounted in a socket 46 provided in the top of a dispensing tube 47 extending into the cartridge 14, the plunger having a base 40' which, FIGURE 2, rests upon an upstanding coil spring 48 supported within the socket 46. The valve plunger 40 projects slidably out of the top of the replaceable cartridge 14. The replaceable cartridge is insertable into the recess 17 so that the projecting part of the valve plunger 40 extends through the outlet port 19 and its free end is within the

bore 26 and is embracingly received within the embracing means or groove 32 in the valve member 30 with a portion of the replaceable cartridge adjacent the top encompassed by the recess 17.

Releasable interengaging means on the replaceable cartridge portion and the wall of the recess 17 detachably secures the replaceable cartridge 14 to the head 12. Specifically, this releasable means comprises a collar 42 which embracingly engages the top portion of the replaceable cartridge 14, FIGURE 5, the collar being provided with opposed lugs 43 projecting from the exterior thereof. The replaceable cartridge 14, upon being inserted into the recess 17, is disposed so that the lugs 43 of the collar 42 are entered in complementary longitudinal slots 44, FIGURE 6, formed in the wall of the recess 17, and the lugs 43 slid along the slots until they engage the entry points of complementary arcuate slots 45 also formed in the wall of the recess 17, whereupon the replaceable cartridge is partially rotated until the lugs 43 are seated in the arcuate slots 45.

The safety razor blade mount 18, FIGURE 5, comprises a guard 50 which overlies and is fixedly attached to the top 20 of the shaving head 12. The guard 50 is provided along each of its sides with spaced elongated slots 52 which are in registry with the adjacent free ends of the legs 29 of the V-shaped passageways 27 of the head 12. Rising from the guard 50 are a pair of anchor bars 51 arranged in longitudinal aligned relation, the bars extending through a longitudinal slot 52 provided in the double-edged safety razor blade 53. The blade 53 is held in fixed mounted position upon the guard 50 by means of a backing member 54 which is hingedly connected to an end of the guard 50 and is swingable from the extended position, shown in FIGURE 5, to a position overlying and engaging the guard 50. The top portions of the anchor bars 51 are embracingly received in a longitudinal slot 55 formed in the under face of the backing member, as shown in FIGURE 2. The backing member 54 is held in mounted position by means of the latch element 56 carried by the backing member and releasably engaging with a hook 57 provided on the guard 50.

It is to be noted that due to the curvature of the guard 50 and the backing member 54, the blade 53, when mounted therebetween, acts to exert a pressure upon the latch element 56 to hold it in tight engagement with the hook 57.

In use of the thus-described replaceable safety shaver, the user grasps the handle or shell 16 with a hand and then positions the shaver so that the side 25 is contiguous to the cheek, whereupon compressive force is applied to the button 34 adjacent the side 23, FIGURE 3. Application of such force causes the valve member 30 to move in the direction toward the side 22 of the head 12, resulting in the shifting of the passage 31 adjacent the side 23 of the head 12 into registry with the apex end 28 of the passageway 27 of the side 25 of the head 12, and shifting of the groove 32 in the valve member 30 out of embracing engagement with the plunger 40 and into depressing engagement with the plunger to thereby depress the plunger 40 to open position followed by the bringing of the plunger 40 in open position into registry with said passage 31 and horizontal groove 31', as shown in FIGURES 5 and 7, and thereby effecting the flow of the shaving lubricant from the replaceable cartridge 14 out of the slots 52 in the guard 50 and onto the cheek of the user. Release of the application of compressive force permits the button 34 to return the valve member 30 to its inoperative position or the position of FIGURE 3, under the action of its associated spring. The same operation takes place upon the application of compressive force to the button 34 adjacent the side 22 and the release of the application of such force to such button, but with the passage 31 adjacent the side 22 of the head 12 shifted into registry with the apex end 28 of the passageway 27 of the side 24 of the head 12 and the plunger 40 in open

position into registry with said passage and the associated horizontal groove 31'.

The replaceable reservoir safety shaver, because of its simplicity of structure, requires no attention other than a cleaning after use, and occasional replacement of the replaceable and disposable cartridge containing the shaving lubricant. Even this replacement may be effected with ease and facility, since all it requires is the detachment of the shell 16 from the head 12, the turning or rotating of the replaceable cartridge 14 in the direction to bring the lugs 43 into registry with the slot 44, applying a withdrawal force to the replaceable cartridge 14 to cause the lugs 43 to travel out of the slot 44, the withdrawal of the collar 42 from the replaceable cartridge and mounting upon the refill replaceable cartridge 14, the insertion of the refill replaceable cartridge so that the lugs 43 are entered in the slot 44, pushing the replaceable cartridge 14 toward the head 12 until the lugs 43 are received within or are engaged by the entry points of the arcuate slots 45, rotating the magazine partially to cause the seating of the lugs 43 in the latter slots 45, mounting the shell 16 so that it encompasses the replaceable cartridge 14 and then detachably securing the open end of the shell to the head 12.

The foregoing description and figures are for illustrative purposes to explain the principle and features of the present invention. In this regard, the shell or handle 16, the replaceable cartridge 14, or shaving head 12, can be of any convenient or desirable shape or size. Further, the slide member 30, although shown as square, may be round, triangular, rectangular, or any other convenient geometrical shape.

The foregoing description, while it deals with a replaceable reservoir shaver of the multiple or double-edged blade, is by no means restricted or confined to such. The presented replaceable reservoir safety shaver can be used for single-edged or injector blades with only minor changes in the shaving head 12, and passageway 27, while the remainder of the shaving unit conforms in principle as illustrated and described.

What is claimed is:

1. In a replaceable reservoir safety shaver, a shaving head having a top, a bottom, and a plurality of pairs of opposed sides between the top and bottom, there being a transverse bore in said head intermediate the top and bottom thereof and extending between one of the pair of opposed sides of said head and opening out of said opposed sides, the bottom of said head being provided with a recess extending inwardly and terminating at a point adjacent said bore, the bottom of said head being provided with an outlet port extending from the terminating point of said recess and opening into said bore, said head having a passageway extending along each of the other pair of opposed sides of said head with one end opening into said bore and the other end opening out of the top of said head, and a valve member mounted in said bore for sliding movement in opposite directions, said valve member being provided with spaced vertical passages and a horizontal groove in association with each passage, sliding movement of said member in one direction bringing one of its passages into communication with said one end of one of said passageways and the associated horizontal groove and sliding movement in the opposite direction bringing the other of its passages and the associated horizontal groove into communication with said one end of the other of said passageways.

2. The replaceable reservoir safety shaver according to claim 1, wherein operatively connected to each end of said valve member and normally projecting out of the adjacent side of said head is a spring-biased operating button, the button serving to effect the sliding movements of the valve member in the respective directions responsive to application of a compressive force applied to a selected button.
